ATTORNEY.

UNITED STATES PATENT OFFICE.

BRUNO VON BÜLTZINGSLÖWEN, OF NEW YORK, ASSIGNOR, BY DIRECT AND MESNE ASSIGNMENTS, TO THE AMERICAN AUTOMATIC KNIFE AND NOVELTY COMPANY, OF BROOKLYN, NEW YORK.

POCKET-KNIFE.

SPECIFICATION forming part of Letters Patent No. 515,045, dated February 20, 1894.

Application filed February 25, 1893. Serial No. 463,727. (No model.)

To all whom it may concern:

Be it known that I, BRUNO VON BÜLTZINGSLÖWEN, a subject of the Emperor of Germany, and a resident of New York, in the county of New York and State of New York, have invented certain new and useful Improvements in Pocket-Knives, of which the following is a specification.

My invention has reference to improvements in pocket-knives of that class in which the blades are inserted from outside and held in position for use by a spring-acted jaw engaging a corresponding notch in the blade, and the invention consists of a handle for pocket-knives, surgical instruments, and the like, having an interior spring that presses upon a pivoted link provided with a jaw adapted to engage a corresponding notch in the blade or other instrument which is inserted with its tang into the upper portion of the handle. The special construction of this handle is more fully described hereinafter and pointed out in the claims.

In the accompanying drawings Figures 1 and 2 are front views of my improved handle for pocket knives, one covering and top plate being removed in Fig. 2. Fig. 3 is a detail showing the intermediate plate for supporting the spring. Fig. 4 is a modification of the handle with a knife-blade attached thereto and one covering and top-plate removed. Fig. 5 shows a button-hook to be used with the handle illustrated in Fig. 2. Figs. 6 and 7 are sections respectively on lines $x-x$ and $y-y$ Fig. 2. Fig. 8 is a second modification of the handle, one covering and one top-plate being removed and the connecting piece of the covering plates in section on line $z-z$ Fig. 9. Fig. 9 is a side view of such modification. Fig. 10 shows a half of the intermediate covering piece used in the handle illustrated in Fig. 8; and Figs. 11 and 12 are sections respectively on lines $a-a$ and $b-b$ Fig. 8.

Similar letters of reference indicate corresponding parts.

The main parts of my improved pocket-knife are the intermediate plate F for supporting the spring f, the pivoted link R upon which the spring presses, the side or covering plates O and the top-plates S. The interme-

diate spring supporting plate F has a slit f' , into which the flat spring f is placed to impart to the same the necessary support, and an incision parallel with the upwardly spring 55 to allow the latter the necessary play. A further incision in the plate F, by which the narrow extension F' (Figs. 2 and 3) is formed, procures the necessary space for the tang of the blade or other instrument. The spring, 60 after being placed into the slit f' and reliably attached thereto, is upwardly bent and presses with its free end against the inner side of the link R which is pivoted by means of a pivot-pin r to and between the intermediate covering-plates O, as shown in Figs. 2 and 6 and in Figs. 8 and 11. The outer faces of the spring-supporting plate F of the spring f and of the link R, form the side-faces of the handle. The portion of the link R, which is 70 engaged by the spring, has a hook or knob d extending beyond one of the side faces of the blade, and the other end terminates in an inwardly extending jaw n. To prevent the link R from being pressed into the handle by the 75 action of the spring, a stop-pin g is fastened to the intermediate covering plates which pin is in contact with the said link, when no pressure is exerted upon the spring from outside, as shown in Figs. 2, 4 and 8. The 80 covering plates O inclose the spring f and the link R, and also the intermediate spring-supporting plate F, to which latter they are fastened by means of rivets or screws. Additional top-plates S are attached to the covering-plates O, as usual in handles for pocket-knives.

The tang k of the knife-blade or other instrument K is provided with one or more notches n' corresponding with the shape of 90 the jaw n.

The intermediate spring supporting plate may consist of one piece or may be composed of the main-part F'' and the narrow part F'. This construction is specially adapted for 95 light handles in which the main-piece F'' may be made of a lighter material for instance, aluminium. If desired, the piece F' may be entirely dispensed with. In this case the covering plates O are made integral with the connecting piece O', which, together with the spring supporting plate F, forms the second 100

side-face of the handle, and may be made separately and soldered to the covering plates.

When the knife-blade or other instrument is to be used with the handle, the hook or knob *d* of the pivoted link *R* is pressed down and the upper end of the same thereby swung outside, so that the opening in the upper portion of the handle is widened, and the blade is then inserted into the said opening. The hook or knob is then released from the pressure and the jaw *n* of the link *R* catches one of the notches in the tang of the blade. Of course the shape of the tang must correspond with the space formed by the extension *F'* and the link *R*. When the jaw *n* has a tapering form and the corresponding notches *n'* of the blades are of a corresponding shape, as shown in Figs. 2 and 5, the blade can be inserted into the handle without pressing the hook or knob *d* down, as, by pushing the tang into the opening of the blade, the link will yield and the jaw catch the notch as soon as it reaches the same. When the blade or instrument is to be released from the handle, the hook or knob *d* is again pressed down, whereby the jaw of the link *R* is disengaged from the notch of the blade and the latter can be removed from the handle.

The several parts of the handle are made of metal, and the top-plates may be made of bone, mother of pearl, or any other suitable material.

My improved handle is specially adapted

for surgical instruments, pocketsets of toilet articles, &c., so that one handle can be used 35 for different knife-blades, button hooks, pincettes and the like.

Having thus described my invention, I claim as new and desire to secure by Letters Patent—

1. In a handle for knives and other instruments, the combination of covering plates, with an intermediate plate having an incision for the tang of the blade and a slit *f'*, a spring placed into the slit *f'*, and an intermediate 45 link pivoted so to the covering plates that the spring presses against the same, substantially as set forth.

2. In a handle for knives and other instruments, the combination of covering plates, 50 with an intermediate plate having an incision for the tang of the blade and a slit *f'*, a spring placed into the slit *f'*, an intermediate link having an inwardly extending jaw and being engaged by the said spring, a stop-pin holding the link in position, and a knife-blade or other instrument having notches which are engaged by the jaw of the pivoted link, substantially as set forth.

Signed at New York, in the county of New 60 York and State of New York, this 8th day of January, A. D. 1893.

BRUNO VON BÜLTZINGSLÖWEN.
